UNITED STATES PATENT OFFICE.

PETER NAPOLEON BRETON, OF MONTREAL, QUEBEC, CANADA.

BOOK-CARRIER.

SPECIFICATION forming part of Letters Patent No. 295,226, dated March 18, 1884.

Application filed October 10, 1883. (No model.) Patented in Canada September 10, 1883, No. 17,601.

To all whom it may concern:

Be it known that I, PETER NAPOLEON BRETON, a Canadian subject of the Queen of Great Britain, and a citizen of Montreal, residing at Montreal, in the district of Montreal and Dominion of Canada, have invented certain new and useful Improvements in Book-Protectors; and I do hereby declare the following to be a full, clear, and exact description of the invention, such as will enable others skilled in the art to which it appertains to make and use the same.

My invention relates to a novel device for holding and carrying an assortment of books, pamphlets, &c., designed mainly for the use of school-pupils in carrying their school-books, stationery, &c., to and from school, or for book-agents, canvassers, peddlers, and others whose duties require the frequent carrying by hand of books and papers; and my said invention consists of a stout and rigid casing composed of two equal-sized sections united by straps, between which casing the books are held and secured; a box or compartment for carrying pens, pencils, and other writing material; a handle for carrying the device; and a water-proof covering for enveloping the entire apparatus, all as will hereinafter more fully appear, and be pointed out in the claim.

This invention has for its object the construction of a simple and convenient device by which to enable school-children and others to carry packages of books and writing material without injury to them, and at the same time provision is made so that in falling weather the entire device and its contents may be enveloped and protected from injury. This is accomplished by the devices forming the subject-matter of the following specification, and illustrated in the accompanying drawings, which form a part hereof; and in which—

Figures 1 and 2 represent a top and bottom view, respectively, of the completed device; and Fig. 3, a front elevation of the same. Fig. 4 is a view in perspective, illustrating the device when in use in falling weather, with the water-proof cover in position over the same.

A and B are two covering-boards, of wood or any other suitable material, and of a size sufficient to fully cover any books or other articles that might have to be carried by them. Near the edges of these covering-boards small slots

are made, through which the straps C C, preferably of leather, are run. Each of these strap embraces both covering-boards, and they are of sufficient length to allow said boards to be separated, so as to take in the required number of books.

D is a box or compartment for holding pencils, pens, or other similar writing utensils, provided with a sliding or hinged lid, D', as preferred.

E is a water-proof cover composed of a top portion, E, and dependent sides E', and of a size sufficient to entirely cover the boards A B and their contents. This protector or cover, when not in use, is rolled up and secured in the cover-straps a a, as shown in Figs. 1 and 3. When desired for use, it is unrolled and spread over the book-protector, as shown in Fig. 4. One end of each of the straps a a is fixed to the covering-board, by tacks a' or otherwise, and the other end is held by hooks or buttons b b, which are screwed or otherwise fixed to the covering-board A, opposite to the tacks a'; or, instead of these hooks or buttons, buckles may be used.

F is the handle by which the device is carried, secured to the cover-board A by fastenings A' at each side thereof.

F' is a slot or opening made in the top portion of the water-proof covering, through which to admit the handle F, by which to carry the device when the water-proof is in use.

By reason of the stout side boards the books are always kept securely in position without liability to be injured, and by the use of the water-proof covering the books are at all times protected from the weather.

The device, or, as I term it, "book-protector," composed of the several parts hereinbefore set forth, forms a very complete and useful article for children and others to carry their books, &c., without injury to the same.

If desired, one or two short buckle-straps may be provided, similar to the ones a a, by which a water-proof cloak or garment may be secured and retained in convenient position for use.

The side boards or sections, A B, are composed of some stout and non-flexible material, preferably wood, whose thickness shall be such as to prevent warping or bending of the same, and they are of a size sufficient to entirely

cover and project some little distance beyond the edges of any books, &c., that may be placed between the same. The object of this is to form a stout and rigid support for the books, 5 that will securely hold them in a flat position, with no liability of injury to the same from the straps, and at the same time protect both their sides and edges from external injury incident to the holder being dropped or struck 10 against.

I am aware that it is not new to employ narrow strips of material placed at the sides or edges of books in connection with straps whereby to secure and carry the same; also, 15 that a water-proof covering has previously been employed in connection with shawl-straps to protect packages of clothing, &c. I do not therefore wish to be understood as laying any broad claim to these features, the gist of my 20 invention relating to details of construction and arrangement going to make up the completed article, as set forth in the foregoing speci-

fication and pointed out in the following claim—that is to say:

I claim as new and desire to secure by Letters Patent of the United States—

A device for holding and carrying books, &c., composed of two side boards or sections, A B, having slots *e* in their outer edges, securing-straps C G, handle F, box or compartment D, and short straps *a a*, adapted for holding a water-proof cover or roll when folded, said cover being constructed substantially as described, and having a slot in its top portion to receive the carrying-handle F, and adapted 30 to be applied to cover the entire device, substantially as and for the purposes described.

In testimony whereof I affix my signature in presence of two witnesses.

PETER NAPOLEON BRETON.
